UNITED STATES PATENT OFFICE.

JOSEPH E. BISSELL, OF PITTSBURGH, PENNSYLVANIA.

INTERNAL-COMBUSTION ENGINE.

1,134,097.

Specification of Letters Patent.

Patented Apr. 6, 1915.

Application filed December 11, 1909. Serial No. 532,707.

To all whom it may concern:

Be it known that I, JOSEPH E. BISSELL, residing at Pittsburgh, in the county of Allegheny and State of Pennsylvania, a citizen of the United States, have invented or discovered certain new and useful Improvements in Internal-Combustion Engines, of which improvements the following is a specification.

10 In the operation of internal-combustion engines such as are in general use today, it is impossible to vary the amount of fuel for succeeding charges, to accord with variation in the amount of power required; but each 15 charge of fuel is of a certain volume, fills a space of definite and unvarying size, and is compressed to the degree necessary to explosion.

The invention herein described has for its 20 object the control of the fuel supply, to the end that the amount of fuel admitted to the explosion chamber for an individual charge may be varied at the will of the operator, the construction being such that though the 25 volume of the charge be thus varied, the degree of compression will not (within the range of ordinary working conditions) be substantially altered.

In the accompanying drawings which 30 form part of this specification, Figures 1 and 2 are sectional elevations of a two-cycle and of a four-cycle engine, each adapted, though in a manner specifically different from that of the other, to the practice of my 35 invention.

In the construction shown in Fig. 1, the engine consists of a cylinder 1 preferably covered with a non-conducting cover 2, so as to retain the heat within the same, to accomplish the useful purpose hereinafter 40 specified. The crank box 3 is closed, and is in free communication with the lower end of the cylinder 1, so that on each down stroke of the piston 4 a compression of air will 45 occur in the crank box or case. The air, so compressed, is forced out through the carbureter 5, which is of any suitable construction, and thence escapes, past the check valve 6, into the expansion chamber 7. The expansion chamber is preferably made as 50 shown, in the form of a tube having a goose-neck at its upper end, such goose-neck connecting with the upper end of the cylinder 1. On the up stroke of the piston, air enters the 55 crank case through a port or opening 9, provided with a suitable check valve 10. The cylinder 1 is provided with an exhaust port 11, so located as to be uncovered when the piston has reached the lower limit of its stroke, or slightly before such limit has been 60 reached. It is preferred that the portion 8 of the explosion chamber, adjacent to the upper end of the cylinder, should be enlarged, as shown in Fig. 1, and that the piston be provided with an extension 12 which, on the 65 up stroke of the piston, enters this enlargement; by such means, the capacity of the explosion chamber may be made to decrease as the piston ascends. It is preferred that the metal walls of the explosion chamber be continuous with the walls of the cylinder, and that these walls be thick, and jacketed with a heat-insulating substance; by such provision, the heat generated in explosion will be absorbed by the walls, and will increase the 70 efficiency of the engine, as will presently be explained.

In Fig. 1 the parts of the engine are shown in position for the ignition of the charge in the explosion chamber, and a dotted line *a* 80 indicates approximately the meeting point of the burned gases above and the new charge below. By the explosion of the new charge, the piston will be forced down, until it reaches the lower limit of its stroke, uncovering the port 11, through which the burned gases will escape, all except a volume of burned gases sufficient to fill the explosion chamber and cylinder at substantially atmospheric pressure. By this same downward 85 stroke of the piston, air and gas will be compressed within the crank case, the carbureter, and the connected passages. On the opening of the exhaust, valve 6 will open under pressure of the gas beneath it overcoming 90 the resistance afforded by spring 13, and a new charge of gas will enter the explosion chamber 7 and will occupy the lower portion thereof, displacing the burned gases so far as necessary. It will be understood that the 95 amount of gas thus entering the explosion chamber 7 will depend upon the tension of the spring 16, which controls the valve 6. It will also be observed that the relative quantity of air entering as one of the ingredients of the explosive mixture will be directly dependent upon the tension of the spring which holds valve 10 to its seat, that being the valve which governs the inflow of air to the crank chamber. By the flow of 100 the explosive mixture into the lower end of the explosion chamber 7, the burned gases

are displaced sufficiently to make room for it, so that, when the piston 4 reaches the lower limit of its stroke, there will be in the lower end of the explosion chamber a volume 5 of explosive mixture at atmospheric pressure (the amount of which is dependent upon the tension of the spring 13 governing valve 6), and that the remainder of the explosion chamber, and the cylinder above the piston 10 4, will be filled with burned gases, at substantially atmospheric pressure. These two volumes or bodies of gas will not mingle to any appreciable extent, but (because of the shape of the chamber and the manner of 15 admitting the new charge) will come into contact with one another at an intermediate point in the length of the explosion chamber 7, such point being indicated in the drawing by the dotted line *a*.
20 It will be apparent that while the amount of air admitted to the crank case on each stroke of the piston, and the amount of explosive mixture admitted to form a charge in the explosion chamber may be varied, as 25 above explained, since the total amount of gas compressed on the up stroke of the piston is constant, the explosive mixture itself (whatever be the actual quantity) will always be brought to the same degree of 30 compression.

In the construction of the four-cycle engine, shown in Fig. 2, the cylinder 1^a is connected at its upper end by a tube 8^a with the explosion chamber 7^a, preferably formed 35 integral with the cylinder, at one side thereof. This chamber is provided with inlet ports 14 and 15, which are controlled by valves 16 and 17, the valve 16 being in the form of a check valve, and normally held 40 to its seat by a spring 18, the tension being adjusted by a nut 19 on the stem of the valve, or in any other suitable manner. This valve 16 controls the inflow of air into the explosion chamber, as hereinafter described.
45 The valve 17, controlling the port 15, through which the explosive mixture passes into the explosion chamber, is provided with a stem 20, which extends down through a suitable stuffing box, and is adapted to be operated 50 in any suitable manner, as by means of a cam or eccentric 21 on the driven shaft 22. This cam or eccentric may be adjusted, to vary the quantity of explosive mixture admitted, by means of a lever 22^a. The explosion chamber 7^a is also provided with a port 55 23, for the escape of the burned gases, products of explosion. This port 23 is controlled by a valve 24, having a stem 25 which extends down through a suitable stuffing 60 box. The valve is normally held to its seat by a spring 26, but may be shifted to open position against the tension of the spring by means of a cam or eccentric 27 on the shaft 22, such cam or eccentric being adjustable, 65 to vary the time of exhaust.

As shown in Fig. 2, the parts of the engine are in position just prior to explosion of the charge. Explosion is effected by means of a spark plug 28, or in other suitable manner. On explosion of the mixture, 70 the piston 4^a will be forced down. On its return stroke, it will drive the burnt gases through the tube 8^a and into the chamber 7^a from which the excess of burnt gases will escape through the port 23—the valve 24 75 being opened simultaneously with the upward movement of the piston. On the next down stroke of the piston, effected by the fly-wheel, the ports 23 will be closed (this will be at or before the beginning of the 80 downward movement), so that, as the piston descends, the pressure of the burnt gases remaining in the piston chamber and in the explosion chamber and the connecting parts, will be gradually reduced below atmospheric 85 pressure, and the extent of the reduction will increase as the piston descends, until the atmospheric pressure on top of valve 16, overcoming the resistance offered by spring 18, will force the valve open, and admit an 90 inflow of air. At a certain point in this second downward movement of the piston, the cam or eccentric 21 will effect the opening of valve 17, thereby admitting an inflow 95 of explosive mixture into the explosion chamber. If the valve 16 has not already been closed by the establishment of an equilibrium of forces operating upon it, the inflow of the explosive mixture through valve 15 will raise the pressure within the 100 explosion chamber to such an extent that the valve 16 will soon close; and, thereafter, explosive mixture only will enter the chamber 7^a, forcing before it such air as has previously entered. On the next upstroke 105 of the piston, which is the compressing stroke, the air and the explosive mixture will be compressed, ignition will follow when the piston reaches the upper limit of its movement. 110

As will be readily understood by those skilled in the art, the quantities of air and of explosive mixture admitted to the explosion chamber 7^a to form the individual charges may be regulated as required, to suit the work to be performed. By shifting the nut 19, the opening of the air valve 16 may accord with different degrees of rarefaction in chamber 7^a; and by the shifting of the cam or eccentric 21, the opening 115 of the valve 17 may be hastened or delayed, as desired. As in the other case, the metal walls of the explosion chamber and of the cylinder are made heavy and continuous, for the absorption and transmission of heat. 120

By admitting the air and the explosive mixture in sequence, as explained above in connection with the description of the engine of Fig. 2, it is found that there is no material mixing of the explosive mixture 125 130

with the air; but that the two, that is the air and the explosive mixture, remain practically segregated during compression and up to the time of explosion.

- 5 In ordinary engine practice, an unvarying quantity of fuel is necessarily consumed on each explosion, and this quantity is necessarily sufficient to afford the maximum of power for which the engine is designed.
- 10 When the engine is required to furnish power in amounts less than its maximum capacity, necessarily a certain amount of the power generated is not employed, but is dissipated as heat, and wasted. The large
- 15 quantities of heat thus generated and dissipated in ordinary practice necessitate the use of cooling means, for otherwise it would be impossible to run the engines for any length of time; one sufficient obstacle to the
- 20 use of an ordinary engine without any cooling agency would be found in the inability of lubricating oils to endure the temperature to which the engine would be heated. The cooling agency ordinarily employed is a
- 25 water jacket, which keeps the temperatures of the cylinder walls at approximately the boiling point of water (212° F.). It has been demonstrated that an internal-combustion engine works most economically when
- 30 the temperature of the cylinder is approximately 300° F.; and, since this temperature is unattainable if a water jacket be used, the alleged superiority of air cooling means is urged, on the strength of this demonstrated
- 35 fact.
- In the use of my invention, I am able to positively control the quantity of fuel supplied from charge to charge, so that not only will the consumption be graded to the demand, but also the heat evolved, instead of being eliminated lest it cause injury, is retained, to the useful end of maintaining the cylinder walls at the most effective temperature. Variation in amount of fuel supply will, if the load upon the machine remains constant, manifest itself in a corresponding variation in the temperature of the walls of the explosion chamber and cylinder.
- 50 One known way of diminishing the supply of power is to advance the spark, so that the gases will be exploded at something less than the maximum compression; but this means waste. Another way is to aerate the explosive mixture to a greater or less degree before its admission to or while it is in the cylinder; but in such practice there is an incidental loss in efficiency. In the practice of my invention, the proportions of the explosive mixture are kept constant, at the point of greatest efficiency, the volume of the charge being adjusted to the conditions of service, and the gases are always ex-

ploded when the charge is at maximum compression. A certain amount of heat generated by explosion is desirable, for I utilize it, as I have indicated above, to maintain the walls of the explosion chamber and cylinder at the temperature of greatest efficiency.

The effect obtained in the use of my invention is analogous to that of the cut-off valve of a steam engine. A definite and predetermined quantity of explosive mixture undiluted with air is introduced to the explosion chamber, compressed to the desired degree, and exploded, and the gases employed expansively, until the pressure is reduced approximately to atmospheric pressure. The relatively small quantity of heat generated is employed to increase the efficiency of the engine, and no cooling means such as an increased radiating surface or a water jacket is necessary. Furthermore, no muffler is necessary, for at the exhaust the burned gases will escape at a pressure but slightly above that of the atmosphere.

I claim herein as my invention:

1. In an internal combustion engine the combination with a cylinder and a piston movable therein, of an elongate explosion or combustion chamber having a supply port at one end and opening at the other end to the said cylinder on one side of the said piston, the said chamber extending without substantial enlargement in width from the gas inlet port to the cylinder.

2. In an internal combustion engine, the combination with a cylinder and a piston movable therein, of an elongate explosion chamber having a supply port at one end and opening at the other end to said cylinder, said chamber extending without substantial enlargement in width from said supply port to the end of said piston when in its extreme inward position within said cylinder.

3. In an internal combustion engine, the combination of a cylinder, a piston, movable therein, an elongate explosion chamber communicating with said cylinder at one end of said piston, and provided with a valve-controlled inlet port at the other end, said chamber extending without substantial enlargement in width from said inlet port to said cylinder, and a non-conducting covering surrounding the walls of said chamber and of said cylinder; the walls of said chamber and of said cylinder affording a path of heat conduction from said explosion chamber walls to said cylinder walls.

In testimony whereof, I have hereunto set my hand.

JOSEPH E. BISSELL.
